METHOD OF MAKING ELECTRICAL CONDENSERS

Philip Ray Coursey, Kingston, England, assignor to Engineering Development Laboratories, Inc., New York, N. Y., a corporation of New York

Original application February 28, 1947, Serial No. 731,507. Divided and this application May 14, 1948, Serial No. 26,997

8 Claims. (Cl. 242—55)

1

This application is a division of Serial #731,507, filed February 28, 1947.

This invention relates to electrical condensers of the kind in which the electrodes and insulating spacers are constituted by interleaved flexible elements of sheet material spirally wound about a central axis, so that the convolutions of the electrode elements, such for example as metal foil, are separated by the convolutions of the flexible spacer elements, such for example as paper or other fibrous or porous material, the rolled unit being usually treated with a suitable impregnant.

According to the specification of the United States of America patent application Serial No. 718,634, dated December 27, 1946, the flexible elements are wound on a single central core held in tension while being rotated about the longitudinal axis of the core which is preferably constituted by a wire driven at both ends simultaneously. It has, hitherto, been found desirable for some purposes to enclose a small condenser of the rolled type within a casing of mouldable material, such for example as Bakelite. The condenser is usually wound, impregnated and the terminal leads attached, this unit being finally enclosed, by means of a moulding press, within the said casing. With this method, however, it is difficult to obtain moisture-proof seals where the terminal leads leave the casing, so that moisture may find access to the rolled condenser within the casing. Moreover, the heat applied during the moulding operation is liable to affect the insulation and electrical qualities of the condenser unit, and one object of the present invention is to overcome these difficulties. A further object of the invention is to provide improvements in or modifications of the core upon which the interleaved flexible elements are spirally wound. These and further objects will become apparent from the appended claims and the following description of the accompanying drawings, in which

Figure 1 is a diagrammatic representation, in side elevation, of apparatus for spirally winding the interleaved flexible elements.

Figure 2 illustrates in vertical section on the line 2—2 of Figure 1, the chucks and winding gear only.

Figures 3 to 6 show on an enlarged scale the steps involved in anchoring the ends of the flexible strips relatively to the core,

Figure 7 shows the rolled unit in side elevation,

Figure 8 illustrates the condenser unit of Fig-

2

ure 7 arranged within a ceramic tube which is shown in longitudinal section.

Figures 9 and 10 are views similar to that of Figure 8 but of modified arrangements.

As shown in Figures 1 and 2, two plastic monofil or similar threads A having an overall diameter of approximately 0.0012 to 0.0015 of an inch are threaded through the axial bores in two aligned rotary chucks B respectively, carried between supports A₁ mounted on a base A₂, one or each of the chucks having an axial micrometer adjustment B₁ (Figure 2) whereby the threads A can be subjected to a required degree of mechanical tension after the core A has been gripped in the chucks B by tightening the heads B₂. The two chucks B are driven, in synchronism, through a handle B₃ and tooth gearing B₄, so that the drive is applied to both ends of the core A simultaneously. Carried by members C, D on the base A₂ with their axes parallel to the axis of rotation of the core A are a plurality of supply rolls two of which C₁, C₂ are constituted by strips of metal foil whilst the two others D₁, D₂ are constituted by strips of paper which are to constitute the insulating spacers between the foils or electrodes. The foils C₁, C₂ have a thickness of, say, not more than five microns (0.0002 inch approximately) whilst the spacers D₁, D₂ may have a thickness of up to 12 microns (0.0005 inch approximately) if used singly or up to 6.5 to 7.0 microns (0.00025 to 0.0003 inch approximately) if used in pairs. Where single paper spacers are used it is sometimes found advantageous to coat one or both sides of them, but preferably one side only, with a layer of lacquer or varnish for the purpose of filling up the irregularities in the paper surface which is adjacent to a metal electrode and so to reduce the liabilities to breakdown through this portion of the tissue.

As shown in Figure 3, the free end of the paper strip D₁ is inserted between the insulating threads A of the core extending between the chucks B so that when the core is rotated by means of the handle B₃ the paper strip D₁ will be wound on the core which then acts as a mandrel until the strip D₁ laps the core as shown. The end of the foil C₁ is taken over two guide rollers E₁ interconnected by an inclined ramp E and thence to the angle formed between the core A and the first paper strip D₁ tangential thereto. The handle B₃ is now turned slightly so that the end of the foil C₁ is wound in, whereupon the end of the second paper strip D₂ is laid over the foil C₁ and thence to the angle between the

strip C₁ and the first convolution of the strip D₁, as shown in Figure 4. Having again turned the handle B₃ through a small angle to wind in the end of the paper strip D₂, the end of the second foil C₂ is laid over a guide roller D₄ and inserted into the angle between the second paper strip D₂ and the adjacent convolution of the first paper strip D₁. The handle B₃ is now turned until the several foils and paper strips are wound as shown in Figure 6, the foils C₁ and C₂ and the second paper strip D₂ being cut so that the strip D₂ extends beyond the ends of the foils. The winding is now completed until the first paper strip D₁ laps the roll whereupon the paper strip D₁ is severed and has its end secured by adhesive as shown at C₃ (Figure 7).

The foils are so wound relatively to the paper spacers that whilst one edge C₄ of the foil C₁ lies wholly within the confines of the paper strips D₁, D₂ the other edge C₅ of the foil C₁ projects beyond the confines of the said paper strips. Similarly one edge C₆ of the foil C₂ lies wholly within the confines of the paper strips D₁, D₂ whilst the other edge C₇ of the foil C₂ projects beyond the paper strips. Thus the two metal foils C₁, C₂ have their marginal edges C₅, C₇ projecting so as to constitute terminal connections for the purpose described below. It will be understood that the distances between the ends of the paper convolutions and the adjacent edges C₄, C₆ of the foils are considerably exaggerated for the sake of clarity of illustration, only narrow margins being actually required in practice. Having cut off the two projecting ends of the core A, the rolled unit shown in Figure 7 is inserted in a ceramic tube G (Figure 8) having internal metallized areas G₁ so that when terminal leads F, F₁ are soldered to the opposite terminal connections C₅, C₇, these are simultaneously soldered to the metallized areas G₁. These soldered connections are such that they provide moisture-proof seals at the ends of the ceramic tube G whose contents, that is to say the rolled condenser elements, are thus sealed against the entry of moisture.

It will be understood that though in the arrangements above described the core is constituted by two insulating threads, the core may be constituted by a single insulating thread, such for example as a synthetic resin, the first flexible element being then merely attached to the core by adhesive. Moreover, since the core is of insulating material and is not employed as one of the condenser terminals, either one of the flexible spacer elements, or one of the foils, may be connected to the core for initiating the winding operation.

The rolled unit shown in Figures 7 and 8 may be treated with an impregnant of mineral wax, oil, jelly or the like, or with an impregnant of high dielectric constant, such for example as one of the chlorinated naphthalenes or chlorinated diphenyls or a wax-like hydrogenated or hydroxylated castor oil, impregnation being effected before the terminal leads F, F₁ are soldered to the terminal connections so as to seal the convolutions of the rolled unit.

When two or more threads are included in the core, for example the threads A in Figures 1 to 6, the threads may be of circular cross-section or in the form of flat strips or other cross-sectional shapes, (e. g. of D-section when twin threads are employed as in Figures 1 to 6) which will fit together to form the requisite cross-sectional profile for the core.

In Figure 9 the rolled unit is as described with

reference to Figure 7 except that the interleaved flexible foils and paper strips are wound on a single core A₃ of insulating material, the first paper strip D₁ being secured to the core A₃ by means of adhesive whereupon the unit is wound as described with reference to Figures 3 to 6 above. Having severed the two ends of the core A₃ level with the projecting ends C₅, C₇ of the foils C₁, C₂, two terminal end plates F₂, F₃ soldered (or otherwise attached e. g. by riveting or welding) to terminal leads F₄, F₅ are themselves soldered to the projecting terminal connections C₅, C₇ and to the metallized areas G₁ within the ceramic tube G, so as to form moisture-proof joints therewith, thus again sealing the rolled unit within the tube G. The sealed unit thus formed is now moulded in a housing of mouldable insulating material H, for example of Bakelite with the terminal leads F₄, F₅ extending from opposite ends of this insulating housing.

In the modification shown in Figure 10 the ends of the ceramic tube G are closed by metallized ceramic plugs J, J₁ which are soldered to the metallized ends G₁ of the ceramic tube G, the terminal leads K, K₁ extending from the terminal connections C₇, C₅ through apertures in the plugs J, J₁ with the leads K, K₁ soldered to the plugs J, J₁ around said apertures, the terminal leads K, K₁ being soldered to the connections C₇, C₅ through metal discs K₂, K₃. Though this condenser may be employed without a surrounding insulating housing, Figure 10 shows the sealed unit moulded within a casing H₁, for example of Bakelite or other mouldable material.

It will be apparent that instead of the tube G being of ceramic material, it may be of metal into which the ceramic plugs J, J₁ are soldered. Alternatively, whether the tube G is of ceramic material or of metal, only one ceramic plug may be used, the other terminal being connected to the metal tube by insertion of a solid disc of metal to close one end of it.

The unit rolled upon an insulating core may, if desired, be disposed and sealed within a metal sleeve or thimble, the sealing being effected by an insulating washer or bush such for example as a ceramic plug through which the terminal lead extends. The sealed unit may then be moulded within a casing of mouldable insulating material, such for example as Bakelite.

While there has been shown and described in the foregoing a preferred embodiment of the invention, it will be understood that various modifications and changes in the construction and methods shown and described herein as well as the substitution of equivalent constructions and steps for those disclosed may be made in accordance with the broad scope and spirit of the invention. The specification and drawings are accordingly to be recorded in an illustrative rather than a limiting sense.

I claim:

1. The method of manufacturing an electrical condenser, according to which a plurality of interleaved flexible conducting and insulating elements are wound spirally upon a rotating core comprising at least one thread of insulating material, while applying mechanical tension to said core during the winding operation.

2. The method of manufacturing an electrical condenser according to which a plurality of interleaved flexible conducting and insulating elements are wound spirally upon a rotating core comprising at least one thread of insulating material, while applying mechanical tension to said

core during the winding operation, the drive being applied to the core at both ends thereof simultaneously.

3. The method of manufacturing an electrical condenser according to which a plurality of interleaved flexible conducting and insulating elements are wound spirally upon a rotating core comprising a plurality of threads of insulating material, while applying mechanical tension to said core during the winding operation.

4. The method of manufacturing an electrical condenser comprising flexible conducting and insulating elements spirally wound about a common axis, according to which a first flexible element is connected to a core held under mechanical tension and comprising at least one thread of insulating material, rotating the core so as to wind said insulating element spirally thereon, and drawing successive flexible elements in between the rotating core and the part of the first flexible element tangential thereto.

5. The method of manufacturing an electrical condenser comprising flexible conducting and insulating elements spirally wound about a common axis, according to which a first flexible element is inserted between the threads of a core comprising a plurality of threads of insulating material, applying mechanical tension to the core while rotating it so as to wind said flexible element spirally thereon, and drawing successive flexible elements in between the rotating core and the part of the first flexible element tangential thereto.

6. The method of manufacturing electrical

condensers of the rolled type comprising spirally winding flexible and insulating layers upon a rotating core consisting of at least one thread of insulating material, and applying mechanical tension to said core during the winding operation.

7. The method of manufacturing electrical condensers of the rolled type comprising spirally winding flexible conducting and insulating layers upon a core consisting of at least one thread of insulating material and being rotatively driven at both ends simultaneously, and applying tension to said core during the winding operation.

8. The method of manufacturing electrical condensers of the rolled type comprising inserting a flexible condenser element between the elements of a core consisting of a plurality of juxtaposed threads of insulating material, applying mechanical tension to said core, and rotating said core while under tension, for winding thereon alternate conducting and insulating layers, to produce a rolled condenser unit.
